TABLE AND FLOOR LAMP

Howard Thornton, Providence, R. I., assignor of
one-half to Carl A. Sjoquist, Cranston, R. I.

Application June 10, 1935, Serial No. 25,865

2 Claims. (Cl. 240—81)

This invention relates to lamps of the table or floor type and has for an object to provide a lamp of this character having a plurality of light bulbs and a novel switch forming a part of the lamp standard and having a rotatable member which may be easily manipulated to energize the lamps singly or in groups.

A further object is to provide a lamp of this character having a novel electric connector in the base for carrying the circuit wires from inside the base to the outside of the base.

A further object is to provide a switch for selectively connecting the supply circuit with branch circuits, the switch being formed of a few, simple, strong and durable parts which are inexpensive to manufacture and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

Figure 1 is a longitudinal sectional view through a lamp constructed in accordance with the invention.

Figure 2 is a bottom plan view of the upper stationary switch member.

Figure 3 is a top plan view of the lower stationary switch member.

Figure 4 is a top plan view of the revolute member of the switch.

Figure 5 is a bottom plan view of the revolute member of the switch.

Figure 6 is a detail longitudinal sectional view of the electrical connector.

Referring now to the drawing in which like characters of reference designate similar parts in the various views, a lamp is shown comprising a hollow standard 10, a base 11 and a hollow cap plate 12 secured to the standard. These parts may all be of metal, the standard being simply a pipe, while both the base and the cap plate are as usual in the form of shells provided with threaded nipples 13 which screw on to the corresponding ends of the standard.

A shade 14 is provided with a spindle 15 which is screwed into an opening in the flat top of the cap plate 12 as is customary. A plurality of incandescent lamp sockets 16, 17 and 18 of conventional type have their nipples 19 secured in

openings 20 in the cap plate as is customary in floor and table lamp construction.

In order that the incandescent lamp bulbs 21, 22, and 23 may be energized singly or by twos, or as an entirety, a novel switch is provided on the standard 10. The switch comprises a stationary disc 24 having an axial opening 25 to receive the standard. A shell 26 is seated at the edge in a recess 27 formed in the disc and is secured to the disc by a screw 28. The shell is provided with an integral boss 29 which surrounds the standard and is secured to the standard by a screw 30. The disc, which is formed of insulating material, is provided preferably with three switch contacts 31, 32 and 33 corresponding to the lamp bulbs 21, 22 and 23. Each contact is seated in a corresponding recess formed in the disc and is provided with a stem 34 which projects above the upper face of the disc. A helical spring 35 is seated in the recess behind the contact and urges 20 the contact downwardly.

A stationary disc 36 similar to the disc 24 is provided with a central opening 37 to receive the standard and this disc is also formed of insulating material. A cap 38 is seated at the edge in a recess 39 formed in the disc 36. A screw 40 is passed through the cap and into the wall of the recess to secure the cap to the disc. The cap is provided with a boss 41 which surrounds the standard and is secured thereto by a screw 42. A single switch contact 43 similar to the switch contacts above described is mounted in a recess in the disc 36 and is urged upwardly by a spring 44 seated in the recess in rear of the contact.

The revolute switch member 45 is a disc of the same diameter as the stationary disc and formed of like material. Likewise the member is provided with an axial opening 46 which loosely receives the standard 10. A knurled edge 47 on the member promotes easy rotating of the member. The member is interposed between the stationary discs 24 and 36 and is confined in position on the standard by the stationary discs. The revolute member 45 is provided in the top face with an arcuate switch contact 48 which is concentric with the opening 46 and is approximately a half circle in rectilinear length. The switch contact is countersunk in the top face of the revolute switch member as best shown in Figure 1. An annular switch contact 49 is countersunk in the bottom face of the revolute switch member and is concentric with and encircles the standard 10. Both of the switch contacts 48 and 49 are connected together by screw bolts 50 and 51 which in addition to assembling the switch

contacts with the member also electrically connect the switch contacts to each other.

By referring to Figure 1 wherein the wiring is shown diagrammatically, it will be seen that the lamp cord 52 enters the standard and one of the wires 53 thereof is led through an opening 54 in the standard and connected to the switch contact 44 in the lower stationary disc 36. Conductor wires 55, 56, and 57 connect the lamp sockets 16, 17, and 18 with the corresponding switch contacts 31, 32 and 33, these wires being concealed within the cap plate and the bore of the standard and passing out of the standard through an opening 58 therein as best shown in Figure 1. The return wire 59 of the lamp cord is concealed in the bore of the standard and in the cap is connected to the return wires 60, 61, and 62 of the lamp sockets 16, 17, and 18.

The revolute switch member 45 may be manually turned to cause the arcuate switch contact 48 to have wiping engagement with one or more of the switch contacts of the upper stationary switch member to energize one or more of the lamp bulbs. For example when the arcuate switch contact 48 is brought into engagement with the stationary switch contact 31 a circuit may be traced through the wire 53, lower stationary switch contact 44, annular switch contact 49, screw bolt 51, arcuate switch contact 48, upper stationary switch contact 31, wire 55, lamp 21 and return wires 60 and 59. When the revolute switch member is turned sufficiently to cause the arcuate switch contact 48 to bridge and have wiping contact with the upper stationary switch contacts 31 and 32, the same circuit above traced will be energized and in addition thereto a circuit will simultaneously be made through the switch contact 32, wire 56 and return wires 61 and 59 whereby both lamp bulbs 21 and 22 will be simultaneously energized. When the revolute switch member is turned sufficiently to cause the arcuate switch contact 48 to bridge all three of the stationary switch contacts 31, 32 and 33, the two above traced circuits will be energized and in addition thereto a circuit may be traced through the switch contact 33, wire 57 and return wires 62 and 59 whereby the lamp bulb 23 will be energized simultaneously with the lamp bulbs 21 and 22. A reversed step movement of the revolute switch member will selectively extinguish the lamp bulbs in sequence reversed from the order above described. Thus it will be apparent that the lamp bulbs may be energized singly or in groups or as an entirety by a simple step rotation of the revolute switch member.

For conducting the circuit wires through the lamp base a connector 63 is employed. As best shown in Figure 6 the connector comprises a socket member 64 which is provided with a flange 65 that is secured to the base 11 by means of

screws 66. The socket is provided with a disc 67 of insulating material in which is mounted contact prongs 68. The circuit wires 53 and 59 are secured to the prongs by screws 69. A flanged cap 70 is screwed on to the socket 64 and affords access to the prongs 68 for applying and removing the circuit wires.

A plug 71 of insulating material is provided with tubular contacts 72 to receive the prongs 68. A cap 73 is threaded on to the end of the plug and is provided with an axial bore 74 which receives a conductor cord 75 the individual wires 76 of which are connected to the tubular contacts 72 by means of screws 77 which are screwed into the ends of the contacts. The cord 75 is terminally equipped with a conventional plug cap 78 for insertion in the floor, wall or other outlet in the usual manner.

From the above description it is thought that the construction and operation of our invention will be fully understood without further explanation.

What is claimed is:

1. In a lamp, a tubular standard, a cap plate, lamp sockets on the cap plate, an upper switch member fixed to the standard, a lower switch member fixed to the standard, a movable switch member revolutely mounted on the standard between the fixed switch members, a plurality of switch contacts arranged in an arcuate row on the bottom face of the upper stationary switch member, an arcuate switch contact on the top face of the movable switch member adapted to bridge the stationary member switch contacts, a switch contact on the top face of the lower stationary switch member, an annular switch contact on the bottom face of the movable switch member disposed in wiping contact with the lower stationary member contact, connectors securing the arcuate switch contact and the annular switch contact to the movable switch member and electrically connecting the arcuate and annular switch contacts together, and circuit wires operatively connected to the switch contacts of the stationary switch members and to the lamp sockets.

2. A switch comprising stationary switch members concentrically mounted, a revolute switch member concentrically mounted between the stationary members, an arcuate series of switch contacts on one of the stationary members, a single switch contact on the other stationary member, an arcuate switch contact on the revolute switch member adapted to have wiping contact with the series of switch contacts on one of the stationary member, an annular switch contact on the revolute switch member having wiping contact with the single switch contact of the other stationary member, and connectors electrically connecting the annular switch contact and the arcuate switch contact together.

HOWARD THORNTON.
